UNITED STATES PATENT OFFICE

JACK SCHWEIZER, OF RYE, NEW YORK, ASSIGNOR TO L. & E. STIRN, INC., OF
NEW YORK, N. Y.

DESIGN FOR A TEXTILE FABRIC OR SIMILAR ARTICLE

Application filed March 31, 1933. Serial No. 47,645. Term of patent 3½ years.

To all whom it may concern:

Be it known that I, JACK SCHWEIZER, a citizen of Switzerland, residing at Rye, New York, have invented a new, original, and ornamental Design for a Textile Fabric or Similar Article, of which the following is a specification, reference being had to the accompanying drawing, forming a part thereof.

The figure is a plan view of a textile fabric showing my new design.

I claim:

The ornamental design for a textile fabric or similar article as shown.

In testimony whereof I have signed this specification.

JACK SCHWEIZER.
